UNITED STATES PATENT OFFICE

MAX WERBER, OF BEACON, NEW YORK

DESIGN FOR A COAT

Application filed November 18, 1929. Serial No. 33,484. Term of patent 7 years.

To all whom it may concern:

Be it known that MAX WERBER, citizen of the United States, residing at 16 North Avenue, Beacon, in the county of Dutchess and State of New York, has invented a new, original, and ornamental Design for a Coat, of which the following is a specification, reference being had to the accompanying drawing, forming part thereof.

The figure shows a front view of the same. The diagonal pockets are the essential or dominant feature of the design.

I claim:

The ornamental design for a coat, as shown.

MAX WERBER.
